UNITED STATES PATENT OFFICE.

WILLIAM ROSE, OF GAINSBOROUGH, ENGLAND.

APPARATUS FOR INSERTING ARTICLES INTO OPEN-ENDED RECEPTACLES, ENVELOPES, SHEATHS, OR CASES.

1,407,581.

Specification of Letters Patent. Patented Feb. 21, 1922.

Application filed January 8, 1921. Serial No. 435,915.

To all whom it may concern:

Be it known that I, WILLIAM ROSE, a subject of the King of Great Britain, residing at Albion Works, Gainsborough, in the county of Lincoln, England, have invented new and useful Improvements in Apparatus for Inserting Articles into Open-Ended Receptacles, Envelopes, Sheaths, or Cases, of which the following is a specification.

This invention relates to apparatus for inserting articles into open-ended receptacles, envelopes, sheaths, or cases, more especially intended for putting together the inner and outer portions of sliding boxes, that is boxes of the kind employed for containing cigarettes, matches, or other articles, and having a tray, or box-proper (which we term the inner member) which is slid into an open-ended envelope, sheath, or case, (which we term the outer member) and for the purposes of description we will presume that the apparatus is to be used for that purpose and from this its application to inserting other articles into open-ended receptacles will also be understood.

The said inner members, and outer members, may be of any suitable material, such, for instance, as thick paper, or card-board.

In an apparatus in accordance with this invention a suitably shaped holder, or support, is held in a stationary position on, the framework of the apparatus and is provided with a side, which can be turned into such a position as to lie in, or about, the same plane as the bottom of the said holder, or support.

The outer members to be dealt with by the apparatus can be delivered, one at a time, onto the said holder, by hand, or by any suitable mechanical means such, for example, as a reciprocable slide moving the said outer members from a vertical pile thereof in a magazine, or from a platform, or the like, in proximity to the said stationary holder, or support.

As the outer members, with which this apparatus is intended to deal, are fed into the apparatus in a collapsed, or flattened, condition, a wedge-shaped, or tapered, device is brought, by any suitable operative

means, into a position to pass into the outer member, and open it by expanding it, or moving apart, the sides thereof.

55

The movable side of the aforesaid stationary holder, or support, is operated in conjunction with the aforesaid wedge-shaped, or tapered, device and a top-plate is operated so as to co-act with the sides and bottom of the said holder, or support, and come against the upper side of the expanded outer member, so that the said outer member is supported, in an opened condition, by the said holder, or support, which, together with its sides and the said top-plate, constitute means by which the outer member is retained in its open condition whilst the aforesaid wedge-shaped, or tapered, device is moving back out of the outer member, and clear of the path along which the box is subsequently moved out of the apparatus.

Supported in proximity to the said holder, or support, is a channel or conductor, provided with a tapered mouthpiece, which may be formed, for example, of strips of flexible steel, or the like.

A reciprocatable first pusher is provided which can be brought to bear against the end of the outer member farthest from the aforesaid mouthpiece, and move the said outer member towards the tapered mouthpiece, until the forward open end of the said outer member is passed over the said tapered mouthpiece.

85

An inner member is, at, or about, the same time, brought into proximity with the aforesaid channel, or conductor, which may be done by hand, or by any other suitable means.

90

A reciprocatable transmitting member operates so as to thrust the inner member along the channel, or conductor, and through the mouthpiece into the outer member, which at this time, is retained in the open position by the aforesaid mouthpiece, stationary holder, top-plate, and first pusher. The aforesaid top-plate now moves away from the upper side of the outer member and, on further forward movement of the transmitting member, and corresponding retiring movement of the first pusher, the outer member, with the inner member in it is moved so as to be freed from the tapered mouth-

95

100

piece, and then the transmitting member retires to its original position and a second pusher acts upon the end of the outer member which has been forced out of engagement with the tapered mouthpiece. At the same time (and preferably by means operative in connection with the second pusher) the first pusher is caused to recede from the outer member, and clear of the path along which it, with the inner member in it, is then caused to travel by the forward movement of the second pusher, which delivers the box from the aforesaid holder, onto, for instance, an endless travelling belt, which removes it, or onto a support, from which it may be removed, to any required place.

I will describe with reference to the accompanying drawings, a construction of apparatus in accordance with this invention explaining how it may be performed, but I do not limit myself to the precise details illustrated.

Figure 1 is a side elevation, Fig. 1^a is a longitudinal section viewed from the opposite side, Figure 2 is an end elevation and Figure 3 is a plan of the apparatus, Figure 4 shews an inner member and Figure 5 shews an outer member (in a partially collapsed condition) of a box such as the apparatus has to deal with.

Figure 6 represents the outer member with the inner member partially inserted therein and Figure 7 shews the inner member, fully inserted.

35 A table 1, is secured by screws 2 to side frames 3 and 3^a which extend upwards from a bed-plate 4.

A main shaft 5 is supported by bearings 6 carried by the side frame 3, and rotative movement can be given to the said main shaft by any suitable means, such for instance, as a belt and pulley, an electric motor, or the like.

Brackets 7, extend from the side frame 3 and support the shaft 8.

The outer members (one of which is indicated at A) of the boxes to be dealt with are deposited by hand, or by any suitable mechanical means, on the table 1, in a partially collapsed condition. Upstanding side pieces 9, and 10, retain the said outer member A, in correct position on the table 1.

A stationary holder, or support, 11, is constituted by a portion of the table 1, fixed side 12, and movable side 13, which movable side is pivotally supported by a spindle 14, in an opening 15, in the table 1, and can be turned down into such a position as to lie in, or about, the same plane as the bottom of the holder, or support, 11. An arm 16, is secured by a boss to the spindle 14, of the movable side 13, and is operably connected by means of links 17, and pins 18, and 19, to the upper end of a lever 20, provided with a boss 21, which is supported so as to be ca-

pable of rocking movement on the shaft 8; a roller arm 22, carrying an antifriction roller 23, being attached to the boss 21. The said roller 23 bears against the edge of a cam 24, which cam 24, is secured to the main shaft 5.

A spring 25 is attached at one end to an extension 16^a of the arm 16, and at the other end to a lug 26, on the underside of the table 1, to keep the roller 23, in contact with the cam 24. A slider 27 is capable of reciprocating movement on a bar 28, rigidly supported by a bracket 29, carried upon the table 1.

A finger piece 30 depends from the slider 27 to effect the transfer of the outer members A, on to the bottom portion 11, of the aforesaid holder, or support.

An arm 31, is connected, at its upper end, by means of a joint-rod 32, and pins 33, and 34, to the slider 27. The boss 35, of the said arm 31, is supported by, and is capable of rocking movement on, the shaft 8, the said boss being provided with an arm 36, carrying an antifriction roller 37, which bears against the edge of a cam 38, secured to the main shaft 5. A spring 39, is attached to a lug 40, on the slider 27, and at the other end to a lug on the stationary bracket 29, to keep the roller 37, in contact with the cam 38.

A wedge-shaped, or tapered, member 41, is provided carried by an arm 42, supported on a slider 43, capable of reciprocating in between guides 44, on the table 1. A spindle 45, is supported by the bearings 46, carried by the bed plate 4. A boss, 47, is supported by, and capable of rocking upon the spindle 45, roller-arm 48, on the said boss being provided with an antifriction roller 49, which bears against a cylindrical cam 50, secured to the main shaft 5.

An arm 51, on the boss 47 is connected at its upper end, by means of a joint rod 52, and pins 53, and 54, to the arm 42. The roller 49 is kept in contact with the cam 50, by a spring 55 attached at one end to a pin 56, on the arm 51, and at the other end to a lug 57 on the side frame 3^a.

An arm 58 has a boss 59, which is secured to the end of a spindle 60, supported in a bearing 61, carried by the table 1, the said spindle 60 being provided at its outer end with an arm 62, carrying an antifriction roller 63, kept against a cylindrical cam 64, (secured to the main shaft 5) by means of a spring 65, attached at one end to a pin 66, on the arm 58, the other end being secured to a lug 67, on the table 1. By these means a top-plate 68, carried on the inner end of the arm 58, situated over the top of the holder, or support, 11, is lifted, and lowered at the proper times.

A channel or conductor 69, is constituted by a portion of the table 1, and upstanding sides 70, and 71, and a tapered mouth-piece 72, including strips 73, of flexible steel, is

situated at the inner end of the said channel, or conductor, 69, in proximity to the holder 11.

A first pusher 74, is carried by a boss 75, supported by a pin 76, on rocking arms 77. A spindle 78, is supported in bearings in bosses 79, and 79^a, on the side frames 3, and 3^a respectively.

The rocking arms 77 are upon a boss 80 secured to the spindle 78, and an arm 81, provided with an antifriction roller 82, is secured to the end of the said spindle 78, the said roller bearing against the cam 83, secured to the main shaft 5, a spring 84, attached at one end to the pin 76, and at the other end to the lug 85, on the bed-plate 4, retaining the roller 82, in contact with the cam 83.

A second pusher 86, is carried by a boss 87, and pins 88, on those ends of the rocking arms 77, which are oppositely disposed to the ends on which the first pusher 74 is mounted.

The ends of a yoke-piece 89, are connected to the pushers 74, and 86, by pins 90 and 91, respectively. A pin 92 is disposed midway between the pins 90 and 91, on the yoke-piece 89, and two links 93, connect the said pin 92, with another pin 94, on the end of an arm 95, carried by a boss 96, secured to a spindle 97, supported in bearings in bosses 98 and 98^a, carried by the side frames 3, and 3^a respectively. An arm 99, secured to the end of the spindle 97, carries an antifriction roller 100 bearing against a cam 101, secured to the main shaft 5, the said roller being kept against the said cam by a spring 102, attached at one end to the pin 94, on the end of the arm 95, and, at the other end, to a stud 103, carried by the underside of the table 1.

A pusher 104, is carried by a slider 105, capable of reciprocating movement in guides 106, on the table 1. A spindle 107 is supported in bearings 108, and 108^a, carried by the side frames 3, and 3^a, respectively, and an arm 109, is secured to the said spindle 107, and a link 110, connects the upper end of the arm 109, with the slider 105, by means of pins 111, and 112. A roller arm 113, secured to the outer end of the spindle 107, is provided with an antifriction roller 114, which is kept in contact with the cam 115, by means of a spring 116, connected at one end to a pin 117, on the arm 109, and at the other end to the aforesaid stud 103. 118 represents a gap provided in the table 1, to allow of the movement of the arm 109.

A delivery channel is provided on the table 1, the said channel having upstanding side pieces 119, and 120, and a slider 121, is capable of reciprocating movement on a slide bar 122, rigidly supported from the table 1, by an extension of the aforesaid bracket 29. An ejector piece 123 depends

from the slider 121. An arm 124 is connected at its upper end by means of a joint-rod 125, and pins 126 and 127, to the slider 121.

The boss 128 of the arm 124 is supported by, and is capable of rocking movement on, the spindle 8, and has an arm 129, provided with an antifriction roller 130, kept in contact with a cam 131, (secured to the main shaft 5) by means of a spring 132, attached, at one end to a lug 133 on the slider 121, and at the other end to a lug 134, on the extended portion of the bracket 29.

The springs 25, 39, 55, 65, 84, 102, 116, and 132, are, for the sake of clearness, omitted from Figure 3.

The hereinbefore described apparatus operates as follows:—

An outer member A, in a collapsed condition is placed on the table 1, between the upstanding sides 9 and 10, and in front of the finger-piece 30. The movable side 13, of the stationary holder, or support, 11, at this time has been, or is, operated from the cam 24, so as to lie in, or about, the same plane as the bottom of the holder, or support 11, and the finger-piece 30, is operated from the cam 38, so as to deliver the outer member A, on to the bottom of the holder, or support, 11, and up to the side 12, thereof and then the movable side 13, is turned up so as to occupy its upright, or closed, position, and at, or about, the same time, the wedge-shaped, or tapered, device 41, is operated from the cam 50, to pass between the upper and lower sides of the outer member A, and open, or expand, it.

The top-plate 68, is now operated from the cam 64 and bears upon the upper side of the outer member A, whilst it is supported in an opened condition on the holder, or support, 11, between the sides 12, and 13.

The first pusher 74, is operated from the cams 83 and 101, to push the outer member A, towards the tapered mouthpiece 72, of the channel, or conductor, 69, so that the opposed open end of the outer member A, passes over the flexible steel strips 73.

The second pusher 86, is, at this time, operated from the said cams 83 and 101, so that it retires out of proximity to the outer member A.

The wedge-shaped or tapered member 41, is at, or about, the same time caused to withdraw from the outer member A, and clear of the path along which the said outer member is to be moved.

The inner member B which has been placed between the sides 70, and 71, on the channel, or conductor, 69, (by hand, or any suitable means) in front of the slider 104 by reason of the movement imparted to it from the cam 115, thrusts the said inner member B, through the tapered mouth piece 72, into the outer member A, which is, at this time,

- retained in proper position by engagement with the flexible strips 73, of the said tapered mouth-piece, the holder, or support, 11 (with its sides) and the first pusher 74.
- 5 The top plate 68, is now, by means of the cam 64, raised from the upper side of the outer member A.
- On further forward movement of the slider 104, and corresponding retiring movement of the first pusher 74, the outer member A, with the inner member B, therein is forced out of engagement with, and to a distance from the flexible strips 73, and the tapered mouth-piece 72, and the slider 104 is 10 operated to make a reverse movement, whilst the second pusher 86 is operated from the aforesaid cams 83 and 101 to come into contact with the end of the outer member A, which has been forced out of engagement 15 with the flexible strips 73, whilst at the same time, and by the same means, the first pusher 74, is caused to recede from the outer member A, (containing the member B) and clear of the path along which it is now made to 20 travel by the second pusher 86 which transfers the box consisting of the outer member A, with the inner member B enclosed therein, clear of the holder, or support 11, and in front of the ejector piece 123, to which movement is imparted from the cam 131 so that 25 the box is delivered between the upstanding side pieces 119, and 120, and out of the apparatus.

What I claim is:—

1. In apparatus of the character described, 35 a stationary holder having a movable side, means for moving said side to a position in which it lies in substantially the same plane as the bottom of the holder, a wedge device for opening and holding open a collapsed 40 receptacle to receive a charge while supported in said holder, together with a top plate and means for moving it into engagement with the top of the receptacle during the withdrawal of said wedge device, substantially 45 as described.

2. In apparatus of the character described, a stationary holder having a movable side, means for moving said side to a position in which it lies in substantially the same plane 50 as the bottom of the holder, a wedge device for opening and holding open a collapsed receptacle to receive a charge while supported in said holder, together with a top plate and means for moving it into engagement with 55 the top of the receptacle during the withdrawal of said wedge device, together with a pusher for advancing the receptacle toward the wedge device, substantially as described.

In testimony whereof I have signed my 60 name to this specification in the presence of two subscribing witnesses.

WILLIAM ROSE.

Witnesses:

E. O. GEORGE,
THOMAS H. PRESTAGE.
